Application June 20, 1941, Serial No. 398,987

34 Claims. (Cl. 93—2)

This invention relates to wrapping machines for wrapping rolls of material, such as rolls of paper towels, toilet paper, or wound rolls of flexible material such as paper cloth and the like.

The machine and method to which the invention pertains is adapted to wrap rolls of material either substantially cylindrical or otherwise, and is particularly adaptable for wrapping cylindrical rolls of flexible material such as toilet paper, paper towels and fabric material. The present machine shown herein is an actual embodiment of a machine now operating in the field for wrapping toilet paper, and while the present machine is described as wrapping rolls of toilet paper, it is just as adaptable for other rolled material such as paper towels and the like. Therefore, while the machine is described in this specification as relating to the wrapping of rolls of toilet paper, the terms herein are illustrative only to the method of wrapping articles of the present character regardless of their dimensions, and the invention is not to be limited to the wrapping of toilet paper merely because the invention has been described in connection with that commodity.

An important object of the present invention is the provision of a new and improved machine adapted to be continuously operated for continuously wrapping rolls of flexible material.

Another object of the invention is to provide a wrapping machine of the class described wherein there is provided a continuously operating conveyor for continuously feeding rolls of material to be wrapped to a predetermined position and then wrapping the rolls successively as they are being continuously fed through the various wrapping, folding and sealing operations.

Another important object of the invention resides in the provision of a wrapping machine which is adapted to wrap rolls of material, the material being rotated prior to the wrapping operation to rewind any unwound portion or extending tails thereon so as to insure a fully wound roll to facilitate proper wrapping.

A further object of the invention is the provision of a new and improved continuously operating wrapping machine embodying new and improved mechanisms operating in timed relationship and in proper synchronism to effect wrapping and folding operations consecutively and in proper timed sequence.

Still another object of the invention is an improved method for completely and securely wrapping rolls of material such as toilet paper, paper towels and other like or similar materials made of paper fabric and the like.

Still another object of the invention is the provision of a wrapping machine having new and improved means for continuously feeding articles to be wrapped to a predetermined position and then causing the articles to be wrapped in a predetermined manner according to a predetermined arrangement, the various mechanisms for effecting the completing of the various wrapping and folding operations being effected while the material passes continuously through the machine.

Another object of the invention is the provision of new and improved means for placing a wrapper about the article with parts of the wrapper extending beyond the ends of the article to be wrapped and then folding in the free ends of the wrapper at various stages during the continuous progressive movement of the material through the machine, there being new and improved means located in a particular manner to effect the proper operations as the articles move continuously through the machine.

Still another object of the invention is the provision of new and improved means for continuously conveying and transferring the articles from one position to another, the various steps of the wrapping and folding operations being accomplished at predetermined positions as the articles pass continuously from one position to another.

Another object of the invention is the provision of new and improved means for passing an article through a wrapper, causing the wrapper to be placed about the article, while the article is being transferred from one continuously operating wheel or conveyor to another continuously operating wheel or conveyor, the transferring taking place while both wheels, the article, and the wrapper are in motion.

Another object of the invention is the position, location and construction of the various parts, all operating in proper synchronism and properly correlated to effect continuous wrapping and folding operations on the article to be wrapped as the article is moving continuously through the machine.

A still further object is the provision of new and improved means for effecting the proper operation of the parts in timed relationship so that the articles may be wrapped at a high speed as they move continuously through the machine.

Numerous other objects and advantages will be apparent throughout the progress of the following specification.

The accompanying drawings illustrate a selected embodiment of the invention and the views therein are as follows:

Fig. 1 is a detail front elevational view of the improved machine;

Fig. 2 is a detail transverse sectional view on the line 2—2 of Fig. 1;

Fig. 3 is a detail longitudinal sectional view taken on the line 3—3 of Fig. 2 at the front end of the machine and showing the intake conveyor;

Fig. 19 is a detail end elevational view of a roll with the wrapper secured thereabout in tubular form;

Figs. 20 and 21 are end elevations of the roll with the wrapper partly folded about the ends thereof;

Fig. 22 is a detail end elevational view of a roll having the folds completed about the ends thereof;

Fig. 23 is a view similar to Fig. 22 but showing an end seal securing the folds in folded position; and

Figs. 24 to 31, inclusive, are schematic views showing various cycles of operation of the package holding, folding and releasing mechanism.

The particular machine herein disclosed for the purpose of illustrating the invention is shown applying and completely folding a wrapper about tubular rolls of toilet paper. This toilet paper wrapping machine comprises a suitable supporting frame 1 including oppositely disposed front and rear walls connected together in any suitable manner, such as by transverse connecting rods or bars.

Intake conveyor

Conveyor mechanism 2 is operatively mounted to the left of the frame or support, Figs. 1 and 3, and is adapted to convey rolls of toilet paper 3 to a transfer wheel 4.

The conveyor 2 comprises spaced chains 5 which lead over suitable driving sprockets 6 mounted on a transverse shaft 7 mounted at the upper part of the supporting frame 1. Other sprockets, not shown, are provided at the opposite end of the conveyor in the usual conventional manner. Each conveyor chain 5 comprises a plurality of spaced apart, pivotally connected links 8, the upper reach of each chain being supported on its under side by a plate or other suitable support 9. Each chain 5 carries a plurality of spaced article conveying members 10 which are pivotally mounted at their forward ends, as indicated at 11, Fig. 3, to a pivot to which the links of the chain are pivotally connected together. The forward ends of the article conveying members 10 are spaced above the normal surface of the chain support 9 and incline rearwardly so that the lower trailing ends rest upon and are supported by the member 9, Fig. 3, so as to prevent forward tipping of the carrying members 10 and to insure that the leading edges will not dig into or otherwise foul the under supports 9. Side rails 12 are mounted on opposite sides of the conveyor to act as side guides for the rolls 3 when they are positioned in the article carrier members 10, Figs. 1 and 2. These side rails or guides 12 are supported in positions intermediate their ends by straps or other holding members 13. Suitable positioned braces or supports 14, Fig. 1, may be provided properly to support the conveyor. The sprockets 6 are continuously driven and drive the continuous chains 5 of the conveyor whereby there is provided a continuously operating conveyor.

The continuously operated conveyor 2 is adapted to deliver rolls 3 continuously and successively to the transfer wheel 4. The article carrying members 10 are adapted to be shifted to proper position to deliver the rolls to the conveyor wheel when they reach practically the end of the conveyor. These article carrying members 10, at the end of their conveying position and just prior to the time the articles 3 are delivered to the transfer wheel and after leaving the under supporting plate 9, engage an arcuate shaped guide 15, Fig. 3. This arcuate shaped guide terminates in a straight surface 16, Fig. 3, which guides the rearward free ends of each of the members 10, and thereby causes the proper tilting position of these members so as to effect the proper delivery of the articles from the members 10 to the receiving members on the transfer wheel 4. This construction and arrangement permits the free delivery of the articles from the members 10 and prevents the members 10 from in any way digging into or otherwise damaging or mutilating the rolls 3. The straight surface 16 acts as a guide for the return of the carriers 10, causing them to attain an inverted position, as clearly shown in Fig. 3. The lower reaches of the chains return the carrying members 10 in an inverted position until they reach the far end of the conveyor, at which time they are again raised into proper operative position. During the return movement of the carrying members 10 they will be supported by an under supporting member 17.

Transfer wheel

The transfer wheel 4, more clearly shown in Figs. 4 and 5, comprises spaced disks 18 integrally connected by a hub 19 which is rigidly secured to a driven shaft 20 which supports and rotates the delivery wheel 4. A plurality of article receiving members 21 extend radially from

the transfer wheel and project outwardly and radially a predetermined distance beyond the outer periphery of the disks 18. Each transfer wheel receiving member 21 comprises parts operatively connected to each of the disks 18. The parts of each member 21 on one disk 18 on one side of the transfer wheel are identical in all respects to the parts mounted on the other disk 18 on the opposite side of the transfer wheel 4. Each transfer wheel carrying or receiving member 21 comprises spaced apart roll supporting members in the form of levers 22 which are pivotally mounted at 23 on pins 24. The pins 24 are arranged in bosses 25 which are formed integrally on the outer surface of each disk 18. Tail pieces 26 extending at right angles to the levers or arms 22 are made integral with these arms 22 and are adapted to control the pivotal movement of the members 22. Rollers 27 are carried at the extreme outer ends of the tail pieces 26 which are adapted to be operated by a cam member for swinging the lever arms 22 inwardly and outwardly. The members 22 are provided on their inner surfaces with a circular tapered protuberance 28 which is adaptable to be received in the central core portion extending transversely through the rolls 3. These protuberances 28 act in effect as an axis or shaft upon which the rolls 3 may be revolvably supported. The inward movement of the levers 22 is limited so that they will move inwardly a predetermined distance properly to support a roll 3 revolvably between faces, but will be prevented from clamping or otherwise squeezing the roll. Springs 29 are mounted on pins 30 which are rigidly secured to the outer surfaces of the disks 18. These springs tend to hold each of the arms 22 inwardly against their stops. These springs 29 also tend to return the levers 22 into proper spaced supporting position when the rollers 27 are no longer under the influence of their operating cams. Spaced cams 31 are arranged on opposite sides of the disks 18 and are adapted to co-operate with the cam rollers 27 on the tail pieces 26 which are rigidly secured to each of the members 22. These cam members 31 are stationary and thus, during rotation of the transfer wheel 4, the holding arms or levers 22 are adapted to be spread apart a predetermined distance to permit an article to be received therebetween or to permit an article to be discharged therefrom.

The transfer wheel 4 rotates in a clockwise direction, Fig. 4, and each article carrying or receiving member 21 is adapted to be spread apart so as to receive an article discharged from the conveyor 2. As the transfer wheel 4 rotates, the levers 22 will be spread apart when a cam roller 27 engages the leading end 32 of the cam 31. Each roller 27, when in position with respect to the leading end 32 of the cam, will cause the levers 22 to be moved outwardly on their pivots 24 to spread the levers 22 the proper distance apart. When the rollers 27 leave the trailing end 33 of the cam, Fig. 4, the cam will have no further influence over the levers 22 and therefore the springs 29 will move the levers 22 inwardly against their stops. The construction and positions of the cams 31 is such that the levers or arms 22 will be spread apart to receive a roll until the conveyor 2 has carried a roll 3 to the position shown in Fig. 3. Immediately after the conveyor 2 has moved a roll to position to be deposited between the spaced arms 22, the rollers

27 will have left the trailing end 33 of the cam 31, at which time the levers or jaws 22 will move inwardly and support the roll revolvably on the protuberances 28.

5 The transfer wheel 4 is so constructed and operates in proper timed relationship with respect to the movement of the conveyor, that an article receiving member 21 will be in proper position with respect to a roll being discharged 10 from the conveyor 2. After a roll is received between the spaced jaws or levers 22 it will be revolvably supported on the members 28 which act as an axis for the rolls, and carried by the transfer wheel to delivery position to a wrapping 15 wheel 34. The delivery position of the roll will be at that point where the cam roller 27 first engages the leading end 32 of the cam 31.

In wrapping articles such as toilet paper there is frequently, if not always, an unwound portion 20 extending from the roll in the form of a tail 35. This unwound portion or tail 35 has always presented a difficulty in the proper wrapping or packaging of the roll. It is therefore desirable and advantageous that this extending tail 35 be 25 rewound on the roll and maintained in such rewound position prior to the wrapping of the roll. In the present embodiment the rewinding, so as to cause the tail 35 to be wound against the roll, is accomplished by engaging a peripheral surface of the roll during its orbital movement 30 against a shoe 36, Fig. 4, having an outer flexible rubber-faced surface 37. The shoe 36 is a hoop-shaped member having one of its ends secured at 38 to the under side of the return rail 17 of the conveyor 2, and its other end secured at 39 to the upper side of the return rail of the conveyor 2, Fig. 4. The member 36 is arcuate, in the form of a semi-circle, commencing at the point 40 and extending to the point 41. The outer surface between the points 40 and 41 is 35 covered with flexible resilient material, such as rubber. The semi-circular portion between the points 40 and 41 is arranged in juxtaposition with respect to the rolls so that the bottom of the rolls will engage the outer rubber surface 37 so that during rotation of the transfer wheel 4 there will be peripheral engagement between the rolls 3 and the rubber semi-circular part 37. This peripheral engagement or physical contact of the roll with the member 37 will cause the individual rolls 3 to rotate in a clockwise direction about their axes comprising the circular tapering protuberances 28. Each roll 3, therefore, is being rotated about its own axis as well as moving in an orbit. Therefore, the unwound portions or tails 35 will be caused to be wound tightly and properly against the balance of the roll and released in that position at the discharge position of the transfer wheel 4. The cam members 31 are each supported by upper and lower posts or supports 42 and 43, Figs. 4 and 5.

Wrapping wheel

65 The wrapping wheel 34 comprises a solid disk 44 which is secured by bolts 45 to a hub 46. The hub 46 is fixed to a transverse shaft 47 which is revolvably mounted in suitable bearings in the frame. The shaft 47 is driven in proper timed 70 relationship with respect to the transfer wheel 4 so as to receive articles properly as they are discharged from the transfer wheel 4. The disk 44 is provided with a plurality of arcuate indentations about its periphery into which there are 75 mounted relatively semi-cylindrical article sup-

ports 48 into which the articles are received progressively as they are discharged from the transfer wheel 4. A plurality of U-shaped first folder arms 49 are pivotally mounted on studs 50 projecting outwardly from the disk 44. The arms 51 of the first folder arms 49 are integrally connected by a cross piece 52 through which pins 53 are slidably mounted. The lower ends of the pins 53 are rigidly connected to a plate 54. Springs 55 surround the pins 53 and tend to urge the plate 54 away from the cross member 52 so as to move the plate 54 against a co-operating plate member 56 fastened to a straight part 57 extending inwardly of the periphery of the disk 44, the pins 53 being provided with washers and cotter pins to limit the movement of the plate 54 away from the cross portion 52.

One of the arms 51 of the U-shaped member 49 is provided with a rigid extension or tail piece 58 which carries a roller 59 for co-operation with a stationary cam 60. The cam 60 is rigidly secured to the frame in any conventional manner, such as by studs or posts 61, Fig. 7. The cam is adapted to control the movement of the members 49 on their pivots 50. The plate 54 carried by the pins 53 is adapted to be moved toward and away from the rigidly secured plate 56 so as to provide a space between the plates 54 and 56 for the reception of the leading edge of a wrapper 62 which is adapted to be wrapped about a roll 3. Thus, when a first folder arm 49 attains a predetermined position prior to arriving at article receiving position from the transfer wheel 4, the cam 60 will cause the arm 58 to be swung on its pivot 50 and raise the clamping surface 54 upwardly away from the rigid clamping surface 56. When the members 54 and 56 are in such spaced position a wrapper 62, which is fed through guide members 63, Fig. 6, will be received between the opposed faces of the members 54 and 56. The inward movement of the wrapper 62 is limited by an extension 64 formed on the rigid plate 56, which, in effect, provides a pocket to receive and properly locate the leading edge of the oncoming wrapper 62. The feeding of the wrapper 62 is such that a wrapper will be fed at the propertime and at the proper position with respect to the open jaws 54 and 56 on the continuously rotating wrapping wheel 34. As soon as the wrapper 62 has been fed between the plates 54 and 56 the cam roller 59 will drop toward the lower surface of the cam, thereby swinging the folder arms 49 on their pivots, and bring the plate 54 into clamping engagement with the plate 56 whereby the wrapper or sheet will be securely clamped between the plates 54 and 56. The continued rotation of the wheel 34 will, therefore, bring the clamped sheet beneath an oncoming roll in the transfer wheel 4. As the wrapping wheel 34 and the transfer wheel 4 continue to rotate, a semi-circular receiving part 48 will be directly beneath one of the article carrying and receiving members 21 of the transfer wheel 4. In this latter position and because of the clamping engagement of the members 54 and 56 with the sheet, the sheet will be properly stretched out or laid over the upper concave surface of the article receiving member 21 on the disk 44. As soon as the concave surface 48 coincides with a roll on the transfer wheel 4, as indicated at A in Fig. 6, a cam roller 27 will engage the leading edge 32 of the transfer wheel cam 31, causing the arms 22 to spread apart and thereby completely release the roll 3 from the transfer wheel 4.

The continued rotation of the wrapping wheel 34 moves the roll from position A in a counter-clockwise direction, Fig. 6, at which time the cam roller 59 will engage a hump 65 on the cam 60, causing the plates 54 and 56 to be again spread apart to unclamp the sheet of wrapping material. However, the sheet will continue to remain in the pocket 64 for a continued cycle of operation. After the sheet 62 has been unclamped between the surfaces 54 and 56, the rear free edge 66, Fig. 6, of a preceding roll 3 will be forced down against the body of the roll 3 by means of a folding blade 67. The folding blade 67 is rigidly secured to the folder arms 49 and includes a folding edge 68 and a concave shoe 69. The edge 68 is adapted to engage the end 66 of the sheet 62 and force it against the body of the roll. The shoe 69 then comes in contact with the peripheral body of the roll and tends to smooth out or iron the wrapper against the body of the roll.

The continued rotation of the wrapping wheel 34 causes the folding blade 67 to press tightly against the wrapper and hold it against the roll, as shown at B in Fig. 6. In this latter position a second folding arm 70 will be caused to engage the wrapper 62 and pull it out of the pocket 64 in the manner clearly shown at position B in Fig. 6. The folder arm 70 comprises a hook-shaped end 71 which is adapted to engage the wrapper and hold it tightly against the roll, permitting the free end 72 of the wrapper to snap out of the pocket 64 and permit it to rest against a guide 73. The folder arm 70 is pivoted on the same pivoted pin 50 so as to permit proper movement toward and away from a roll. The folder arm 70 comprises a pair of spaced arms 74, one of which carries a rigid extension or tail piece 75 upon which there is revolvably mounted a cam roller 76. The cam roller 76 is adapted to ride on the peripheral surface of a stationary cam 77 which is rigidly secured to the frame by means of bolts or studs 78. This cam 77 is provided with a raised surface 79, and a lower surface 80 which controls the operation of the folding arms 70. Thus, when a cam roller 76 is on the hump or high spot of the cam 77, the folder arms 70 will be removed or spaced from the roll, but when the cam roller 76 is on the low part 80 of the cam, the folder arms 70 will be brought into engagement with the wrapper to force the wrapper against the roll. When a roll arrives at the position indicated at B in Fig. 6, the folding blade 67 will hold the rear free trailing edge 66 of the wrapper against the roll, while the forward leading edge of the wrapper will be bent downwardly from the forward end of the hook-shaped end 71 of a second folder arm 70. The part of the wrapper projecting from the end 71 of the second folder arm 70 will be against a guide 73 where it will be in a position to be fed for physical contact by a glue stencil 81 by the continued counter-clockwise rotation of the wrapping wheel 34.

The glue stencil 81 is adapted to wipe against the peripheral surface of a driven glue roller 82 which extends downwardly a predetermined distance into the glue or other adhesive substance 83, Fig. 6, in a receptacle 84 formed in the glue housing 85. The elements 81 and 82 are mounted on shafts 86 and 87, respectively, suitably mounted in bearings in the glue housing frame 85, which is rigidly secured to the main frame of the machine. The glue stencil 81 is adapted to apply a predetermined amount of glue or other adhesive along the entire longitudinal edge of the wrapper and on the inner sur-

face thereof so that it will be glued to the exterior or outside surface of the trailing edge of the wrapper. A guide 88 is positioned adjacent the glue stencil 81 and has a arcuate surface concentric with the glue stencil so as to insure the end 72 of the wrapper, Fig. 6, definitely contacting the surface of the glue stencil to have the proper amount of glue applied thereto. A scraper 89, Fig. 6, is arranged adjacent the glue roller 82 to insure the proper thickness of glue on the surface thereof to be transferred to the stencil 81.

Auxiliary folding mechanism

Auxiliary folding mechanism 90 is adapted to insure the proper overlapping of the edges of the wrapper about the roll by tucking in the extreme edge of the trailing end 66 of the wrapper 62. This auxiliary folding mechanism 90 comprises a pair of auxiliary folding blades 91, each of which operate on alternate successive rolls as they are moved to proper position. Each folding blade 91 and the means in which it is operated are identical and, therefore, only one need be described. The folder blade 91 is mounted on an arm 92 and extends forwardly therefrom in the position shown in Figs. 6 and 6a. The arm 92 is pivotally connected at 93 to a lever 94 rigidly secured to a driven shaft 95. A cam roller 96 is operatively secured to the arm 92 and is adapted to engage a cam race 97 formed in a stationary cam 98 rigidly secured to a part of the frame. Rotation of the shaft 95 therefore causes each arm 92 to move in an orbit, but the shape of the cam it such that the folding blade 91 is moved into engagement with the wrapper and then forced to back away at the proper time. The purpose of the auxiliary blade 91 is to hold the edge 66 of the wrapper 62 firmly against the body of the roll 3 and cause this edge to be tucked under the leading edge 72 of the wrapper as it passes over a rotary mounted presser roll 99. The roll as it moves from the position indicated at B in Fig. 6, therefore, will have the leading edge of the wrapper on its under side glued and then caused to be properly pressed against the roll 3 by the presser roll 99 and securely wiped or ironed to the outer surface of the trailing edge 66 of the wrapper 62. The folder 91 moves forwardly into engagement with the trailing edge 66 of the wrapper 62 a predetermined distance but not sufficient to come into contact with the presser roller 99. The continued rotation of the wheel 34 thus draws the leading edge of the wrapper underneath the presser roller 99, causing it to be glued to the trailing edge 66 of the wrapper 62. As soon as the trailing edge of the wrapper 62 arrives substantially at the presser roller 99, the auxiliary blade 91 will retract and move away from the roll.

The continued rotation of the wheel will cause the presser roller 99 to press the longitudinal glued seam to insure proper adhesion. The presser roller 99 is substantially as long as the width of the wrapper 62 and is mounted to roll against a roll 3 as it is being moved by the wrapping wheel 34. The presser roller 99 is supported on arms 100 which are pivotally mounted at 101, Fig. 6, to a part of the frame. Springs 102 are positioned beneath the lower end of the arms 100 to urge the arms 100 and consequently the presser roller 99 toward the periphery of the wrapping wheel so as to provide spring pressure against the seam of the package as the wrapping

wheel carries the roll past the presser roller. The glued edges are maintained in proper contact during continued rotation of the wheel by a flexible weighted strap 103, Fig. 6. This strap 103 has its leading end to the left, Fig. 6, rigidly secured to a part of the machine frame and its lower end passing over a pin 104, Fig. 6, mounted on part of the machine frame. The free end of the member 103 is provided with a weight 105 so as to cause the flexible member 103 to engage the roll at the glued seam. The glued seam is in continuous contact with the flexible member 103 and the roll at the seam is pressed or wiped against the flexible member 103 so as to maintain the wrapper in proper glued contact for a predetermined distance of travel, after which time the glue has dried sufficiently to cause the seam to be properly sealed. The weight 105 is to provide for proper flexibility and to create the proper amount of pressure against the glued seam.

After the two free edges of the wrapper have been glued together to form a glued seam 106, Fig. 19, the wrapper, which is now in tubular form about the roll with the ends of the wrapper extending a predetermined distance beyond the edge of the roll, as shown in Fig. 19, is now in position to have the tubular extensions 107 on each end of the roll forced down against the ends 108 of the roll 3.

The means for folding the projecting ends 107 of the now tubular wrapper extending beyond the ends of the roll comprises rotary end folders 109 and stationary end folders 110, Figs. 10, 13, 35 and 13a. The rotary end folders 109 comprise folder arms 111 rigidly secured to driven shafts 112. The driven shafts 112 are suitably mounted in bearings provided in the machine frame and carry bevel gears 113 which mesh with companion bevel gears 114 on a shaft 115. The shaft 115 is driven from a gear 116 fixed to one end of the shaft 115, Figs. 10 and 13. The folder arms 111 of the rotary folder 109 rotate continuously and are timed with respect to the movement of the wrapping wheel 34 so that when a roll reaches a predetermined proper position the folder arms 111 will engage the projecting tubular extension 107 on each end of the roll and press the extension downwardly against the opposed faces 108 of the roll. Substantially at the same time the rotary folder arms 111 engage the extension 107 to make the first folding operation, the package will be moved against the stationary opposed folders 110 and cause the tubular extension 107 to be also folded inwardly against the opposed ends 108 of the roll, whereby the extending end of the wrapper will assume the position shown in Fig. 20. The stationary folders 110 are relatively long and maintain the folds caused by both the rotary folder 109 and the stationary folder 110 to be maintained in folded position tightly against the surfaces 108 of the roll. The roll is then brought into a second folding position by the rotative movement of the wrapping wheel 34.

The means for effecting the next or subsequent folding operation comprises a pair of opposed second end folders 117 which are substantially drum-shaped, as shown in Figs. 10 and 14. These rotary drum-shaped folder members 117 comprise a rigid forwardly extending finger 118 which is positioned in a relatively V-shaped space or opening provided in the periphery of the drum and has its rear end spaced a predetermined distance from the base of the V. The sides of the

drum in cooperation with the V. opening provide a pair of bifurcated fingers 120 and 121 which extend on opposite sides of the finger 118 and cooperate with the finger 118 in folding down the lower portion 122 of the extending wrapper 107, Fig. 20. One side of the member 117 is also cut away in spiral form, as indicated at 119, Fig. 10. The arrangement is such that the spaced apart fingers 120 and 121 are spaced rearwardly a predetermined distance from the forward edge of the member 118 so that during rotation of each drum 117 the finger 118 will first engage the outside of the lower unfolded portion 122 of the extending wrapper 107 and tuck the extending wrapper inwardly to form a lower center fold 123, Fig. 21. Shortly thereafter, the fingers 120 and 121 engage the wrapper to fold down the wrapper to provide the folds 124 on opposite sides of the first pressed down part 123, as shown in Fig. 21. During the folding operation of the lower part 122 of the wrapper, the members 118, 120 and 121 will engage the wrapper in the manner shown in Fig. 21, and force the wrapper tightly downward against the ends of the roll. The peripheral surface of the drums 117 during the rotation of the drums completes the folding operation and presses the folds tightly and securely against the opposed faces 108 of the wrapper to complete the folding operation, as shown in Fig. 21. The second end folders 117 are each mounted in supporting brackets or journals 125 which revolubly support shafts 126 upon which the drums 117 are rigidly secured. The shafts 126 carry bevel gears 127 which mesh with bevel gears 128 mounted on a driven shaft 129, Fig. 10. After the completion of the folding operation by the second end folders 117 the package will be completely folded with the exception of the projection portion of the wrapper indicated by the numeral 130 shown at the upper part of Fig. 21. The previously formed folds are maintained in folded position and held against the ends 108 of the roll 3 by means of stationary guides 131, Fig. 10. The space between the guides 131 is substantially equal to the width of the roll.

In order to complete the folding operation, third end folders 132 are provided, Figs. 10, 11, and 15. These third end folders are identical in construction and operation to the previously described end folders 117 and include the spaced apart drums having the forwardly extending fingers 118, edges 119, and the co-operating folding fingers 120 and 121. The third end folders 132 are properly timed with respect to the rotation of the wrapping wheel and with each other and are to complete the folding operation. The finger 118 engages the projecting unfolded part 130 of the wrapper on each end thereof, presses the wrapper inwardly toward the center of the roll, and then is immediately followed by the two other folding fingers 120 and 121 to fold the part 130, Fig. 21, downwardly and tightly against the ends of the roll to finish the folding operation, as shown in Fig. 22. The drums of the third folders 132 are mounted on shafts 133, Figs. 11 and 15, which carry bevel gears 134 meshing with bevel gears 135 which are preferably secured to spur gears 136. The spur gears 136 mesh with gears 137 fixed to a transverse driven shaft 138. The rotation of the third end folders 132 folds the last named folds or tucks 139, 140, and 141, Fig. 22, tightly against the end of the roll and properly crease the wrapper. After the completion of the operation of the third end folders 132 the rolls 3 are moved to position to be operated

upon by presser rollers 142 during the continued rotation of the wrapping wheel 34. As the wrapping wheel 34 moves the roll toward the presser rollers 142 the opposite ends of the roll will contact with spaced guides 143, Fig. 10, to maintain the folds or pleats in proper position tightly against the ends of the roll.

Presser rollers

The presser rollers 142, Figs. 11 and 15, are positioned to engage the opposite ends of the roll to press against, roll out and flatten the pleats and folds previously made by the various folding operations. These presser rollers are positioned beyond the third set of end folders 132 and beyond the stationary guides 143. These rollers 142, as more clearly shown in Figs. 11 and 15, are mounted on shafts 144 mounted in suitable bearings 145 secured to the machine frame. These shafts each carry a bevel gear 146 which meshes with companion bevel gears 147 fixed on a transverse shaft 148. The ends of the rolls are therefore pressed down by the rollers 142 as the wrapping wheel 34 moves the rolls 3 to a position to be discharged on a receiving conveyor 149. As the wrapping wheel 34 moves the roll to position to be discharged therefrom the cam roller 76 on the hook-shaped second folders 10 will be released from the roll 3, because the high spot 150 on the cam 80 will cause the hook-shaped arms 71 to be swung away from the roll 3. Substantially at the time the cam roller 76 engages the high spot 150 on the cam 71 the cam roller 59 will engage a high spot 151 on its co-operating cam 60 and therefore cause the first folder arms 49 to be released from package engagement. The parts will then be in the position as indicated at C in Fig. 6 so as to receive another roll to be wrapped. The action of the points 150 and 151 on the cams 71 and 60 in co-operation with the respective cam rollers 76 and 59 will cause the parts to move from the position shown in Fig. 29 and assume the position shown in Fig. 30. As soon as the wrapping wheel 34 has moved the roll to the position shown in Fig. 29, the article receiving members 152 on the conveyor 149 will be in substantial engagement with the roll, as shown in Fig. 29, and as the wrapping wheel continues to rotate, the parts will be spread apart to the position shown in Fig. 30, at which time the article receiving members 152 on the conveyor will engage the articles and deliver them to a predetermined position by the conveyor mechanism 149. During the transfer of rolls 3 from the wrapping wheel 34 to the receiving conveyor 149 the rolls will be positioned between spaced guide plates 153 to maintain the folds in proper folded position. Also, in assisting in directing the rolls to the conveyor, and to prevent the rolls from continuing in the wrapping wheel 34, there are provided spaced arcuate shoes 154. These shoes assist in preventing the rolls from being released from the article receiving members 152 of the conveyor mechanism 149.

After the rolls have been properly received on the conveyor mechanism 149 they are conveyed to another station to have seals applied over the folded ends of the rolls as shown in Fig. 23. The mechanism for applying these latter named seals and the method of application are disclosed and claimed in applicant's co-pending application Serial No. 398,988, filed concurrently herewith and assigned to the present assignee.

The conveyor mechanism 149 comprises chains 155 trained over sprockets 156 which are loosely

Operation

mounted upon the previously described shaft 148. The driving sprockets, not shown, for the conveyor 149 are located at the opposite end of the conveyor mechanism 149 for driving the chains 155. The construction of the conveyor mechanism 149 is substantially the same as the previously described feeding or intake conveyor mechanism 2. The conveyor mechanism includes upper spaced guides 157 to engage the opposite ends of each roll 3 as it is being conveyed by the conveyor. The carrier members 152 are attached to the chain 155 and there are supports for the upper reach of the chain as well as a lower return guide for the carrier members 152 the same as those previously mentioned with respect to the conveyor 2. Arcuate guides 158, Fig. 10, are provided to maintain the carrier members 152 in proper position as they are being carried upwardly from the lower reach of the conveyor to the upper reach thereof.

The mechanism and the operating parts are all operated synchronously and in proper timed relation. The parts are driven from a motor 160, Fig. 17, which is mounted on a part of the main frame 1. The motor shaft 161 is provided with a V-shaped pulley 162 for driving the V-shaped belts 163. The belts 163 operate a pulley 164 which is secured to a main drive shaft 165. A clutch 166 is interposed between the drive wheel 164 and the drive shaft 165 for the usual purpose, Fig. 17. The clutch is adapted to be operated by means of a handle 167 and its interconnected mechanism. A gear 168, Fig. 17, is rigid with the drive shaft 165 and drives a gear 169 mounted on a transverse shaft 170 suitably mounted in the machine frame. The shaft 170 extends through the side of the frame and carries a main drive gear 171, Fig. 17. The main drive gear 171 meshes with a gear 172 on the shaft 138 which controls the operation of the third end folders 132. The gear 172 meshes with a gear 173 fixed on the transverse shaft 148 for the purpose of driving the presser rollers 142. The main drive gear 171 also meshes with a gear 174 on the shaft 129 for driving the end folder mechanism 111. The gear 174 drives the gear 116 on the shaft 115 through the idler gears 175 and 176, Fig. 18. A gear 177 secured to the idler gear 176 drives an idler gear 178. The gear 178 has fixed thereto a smaller gear 179 which meshes with and drives a gear 180 on the shaft 47 which shaft rotates the wrapping wheel 34. The gear 180 meshes with and drives an idler gear 181 which, in turn, drives another idler gear 182. The idler gear 182 meshes with and drives a gear 183 fixed onto the shaft 20 which drives the transfer wheel 4. The idler gear 182 also has meshing relation with a gear 184 on the shaft 7 which drives the intake conveyor mechanism 2. An idler gear 185, Fig. 18, is driven by the gear 116 on the shaft 115 and rotates a gear 186 which is fixed to the gear 185. This gear 186 drives a gear 187 on the shaft 95 which supports and drives the auxiliary folding mechanism 90. The shaft 95, which is driven by the gear 187, carries a gear 188 which meshes with and drives a gear 189, Fig. 9, supported on a stud shaft 190. The gear 189 is fixed to a gear 191 which has meshing relation with a gear 192 fixed on the shaft 86 which drives the glue stencil 81. This latter gear 192 has meshing relation with a gear 193 on the shaft 87 upon which the glue roller 82 is mounted. The driving connections and mechanisms are such that positive synchronized operation of all the parts is assured.

The mechanism is driven by the main motor 160, Fig. 17, and the operation of the parts is controlled by the clutch lever 167. Rolls 3 are fed into the carrier members 10 and conveyed to position with respect to the transfer wheel 4. The transfer wheel takes each successive roll as it reaches a predetermined position. As the rolls leave the conveyor 2 they are fed between the spaced apart jaws or arms 22 where the rolls are revolvably suspended. As the transfer wheel 4 rotates the periphery of each roll will engage the flexible facing 37 and because of the continuous rotation of the transfer wheel 4 the rolls 3 will be given independent rotary movement about their axes, thereby causing the unwound or tail part 35 of each roll to be securely wound tightly about the roll. The transfer wheel delivers each successive roll to position to be received by the wrapping wheel 34. When a roll attains the position indicated at A in Fig. 6, the levers 22 will be released and the roll will then be received in a cylindrical pocket 48 of the transfer wheel. The transfer wheel 34 is a continuously operating wheel and moves the rolls to predetermined positions continuously and progressively to have the various wrapping operations performed. Wrapping material 62, Fig. 6, is fed between the clamping plates 54 and 56 carried on the first folder arms 49 and on a rigid surface on the wrapping wheel, respectively. The cam 60 co-operating with the cam roller 59 on the first folder arms 49 causes the folder arms to attain clamping engagement with the clamping plate 56. A sheet of wrapping material 62 is then drawn into position because of the rotation of the wrapping wheel 34, whereby the wrapping material 62 will be spread across a pocket 48. As the wrapping wheel moves the pocket with the wrapper toward the position to receive a roll from the transfer wheel 4, as indicated at position A in Fig. 6, the parts will assume the position shown in Fig. 24, whereby the paper is clamped between clamping members 54 and 56 at the extreme left hand edge of Fig. 24. The wrapper is then arranged beneath the incoming roll 3 which will then be received in the cylindrical receiving member 48 in the wheel 34. The next succeeding first folder arm 49 will then have the folding blade 67 away from the roll but engaging the under side of the wrapper 62, as shown in Fig. 24. The continued movement of the wrapping wheel 34 then causes the parts to assume the position shown in Fig. 25, and then subsequently the position shown in Fig. 26. In Fig. 26 the cam roller 76 is operated by the cam 77, thereby moving the folding lever 70 into engagement with the roll, as shown in Fig. 26. In this latter position the first folder blade 67 will be removed from the roll 3 but will be caused subsequently to contact the roll, as shown in Fig. 27, because a cam roller 59 is being controlled by the cam 60 to move the folder arms 49 toward the roll. The roll will then be clamped by the first folding arms 49 and the second folding arms 70, as clearly shown in Fig. 27. In Fig. 27 the trailing edge 66 of the wrapper 62 will be extending a predetermined distance beyond the end of the first folder blade 67, while the leading edge 72 of the wrapper 62 will be in the position shown in Fig. 27, with its inner surface in contact with the guide 73. The continued rotation of the wrapping wheel 34 with the roll securely clamped between the members 49 and 70 brings the roll in position so that the free edge 72 will be grasped between

the glue stencil and the backing member 88 to have glue applied thereon. The continued rotary motion of the wrapping wheel will then cause the edge 72 to be withdrawn so as to be glued against the trailing edge 66 of the wrapper by means of the presser roll 99, Fig. 6a. Just as the leading edge 72 is about in position to be wiped over the trailing end 66 the auxiliary folder 91 will be moved into physical contact with the trailing end 66 of the wrapper 62, as shown in Fig. 6a. The continued movement of the wrapping wheel 34 will cause the glued leading end 72 of the wrapper 62 to be pressed against the trailing edge 66 of the wrapper 62, at which time the auxiliary folding member 91 will retract and be moved away from the article. The wrapper 62 is then arranged about the roll in tubular form, as shown in Fig. 19, and the roll will be securely held between the first folder arms 49 and the second folding arms 70, and the auxiliary folding blade 91 will be retracted, as shown in Fig. 28. The continued rotation of the wrapping wheel 34 then causes the protruding tubular ends of the wrapper to be folded first by the rotary end folders 109 and the stationary end folders 110. After this latter folding operation the lower folds 123 and 124 will be made by the second end folding mechanism 117, whereby the roll will be wrapped, as shown in Fig. 21. The third end folding mechanism 132 will then operate on the remaining unfolded part of the wrapper when the wrapping wheel 34 has moved the roll to position to be operated upon by the third end folding mechanism 132. The presser rollers 142 then bear against and roll the ends of the wrapper which have been completely folded down in the manner shown in Fig. 22. The completed rolls are then fed to position to be received by the receiving conveyor 149. From the time the rolls are glued and seamed until the time the rolls are removed from the wrapping wheel 34, and during the various end folding operations, the glued seam will be in contact with the flexible member 103 so as to insure the proper gluing of the parts of the wrapper together along the seam 106. Just prior to the time the rolls are removed from the wrapping wheel 34 the cam rollers 59 and 76 will be caused by their respective cams to release the first folder arms 49 and the second folding arms 70, as shown in Fig. 30. The release of the arms 49 and 70 takes place just about the time the receiving members 152 on the conveyor 149 come into position to receive the roll. The carrying members 152 then move the rolls to a predetermined position, and the members 49 and 70 will be in the position shown in Fig. 31 and again ready to repeat the cycle of operation.

The invention provides a machine which feeds rolls of material, such as rolls of toilet paper, continuously by a continuously operating conveyor to a continuously operating transfer wheel which, in turn, feeds the rolls successively to a continuously operating wrapping wheel where the various stages of the wrapping and folding is completed. After the rolls are completely wrapped they are then moved to a second continuous conveyor which delivers them to a predetermined position. The parts are rigid and durable in construction and are adapted to operate continuously and in proper timed relationship. The machine is efficient in operation and is so constructed as to minimize repairs and upkeep.

Changes may be made in the form, construction and arrangement of the parts without departing from the spirit of the invention or sacrificing any

of its advantages, and the right is hereby reserved to make all such changes as fairly fall within the scope of the following claims.

The invention is hereby claimed as follows:

1. A machine for wrapping rolls of wound material comprising a continuously operating conveyor for conveying said wound rolls to be wrapped to a predetermined location, means for rendering movement to said rolls to rewind unwound parts thereof, means for delivering said rewound rolls to a predetermined location, and means for receiving said rewound rolls at said last named predetermined location and applying a wrapper about said rolls.
2. A machine for wrapping wound rolls of material comprising a continuously operating conveyor for conveying said wound rolls to be wrapped to a predetermined location, means for rendering movement to said rolls to rewind unwound parts thereof, means for delivering said rewound rolls directly to a wrapping wheel, means for rotating said wheel, and means for applying a wrapper to said rolls while entering the rotating wheel.
3. A machine for wrapping wound rolls of material comprising a continuously operating conveyor for conveying said wound rolls to be wrapped to a predetermined location, means for rendering movement to said rolls to rewind unwound parts thereof, means for delivering said rewound rolls directly to a wrapping wheel, means for applying a wrapper on each roll successively as the rolls are moved by the wheel, and means for folding the ends of the wrapper against the ends of each roll while the rolls are on the rotating wheel.
4. A wrapping machine comprising means for delivering articles to be wrapped to a predetermined position, continuously rotating means for receiving articles successively from the delivery means, means for feeding a wrapper to the continuously rotating means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, and means for causing the first free end to be applied over the second named free end.
5. A wrapping machine comprising means for delivering articles to be wrapped to a predetermined position, continuously rotating means for receiving articles successively from the delivery means, means for feeding a wrapper to the continuously rotating means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, and means for causing the first free end to be applied over the second named free end, and means for thereafter folding the wrapper tightly against the

ends of each roll while the roll is on the continuously rotating means.

6. A wrapping machine comprising means for delivering articles to be wrapped to a predetermined position, continuously rotating means for receiving articles successively from the delivery means, means for feeding a wrapper to the continuously rotating means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, means for causing the first free end to be applied over the second named free end, oppositely disposed rotary mounted means for folding the wrapper partially across the opposed ends of the article, and stationary means opposite the rotary means and operating on the wrapper to effect a similar fold on each end of the article opposite to each fold made by the rotary members.

7. A wrapping machine comprising means for delivering articles to be wrapped to a predetermined position, continuously rotating means for receiving articles successively from the delivery means, means for feeding a wrapper to the continuously rotating means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, means for causing the first free end to be applied over the second named free end, oppositely disposed rotary mounted means for folding the wrapper partially across the opposed ends of the article, stationary means opposite the rotary means and operating on the wrapper to effect a similar fold on each end of the article opposite to each fold made by the rotary members, and oppositely disposed rotary members for folding a half of the unfolded portion against the wrapper in a plurality of overlapping folds.

8. A wrapping machine comprising means for delivering articles to be wrapped to a predetermined position, continuously rotating means for receiving articles successively from the delivery means, means for feeding a wrapper to the continuously rotating means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, means for causing the first free end to be applied over the second named free end, oppositely disposed rotary mounted means for folding

the wrapper partially across the opposed ends of the article, stationary means opposite the rotary mounted means and operating on the wrapper to effect a similar fold on each end of the article opposite to each fold made by the rotary mounted means, oppositely disposed rotary members for folding a half of the unfolded portion against the wrapper in a plurality of overlapping folds, and means operating subsequently to said last named means for effecting a similar fold on the remaining unfolded portion of the wrapper to completely fold the wrapper about the ends of the article.

9. A wrapping machine comprising an endless conveyor for delivering wound articles to be wrapped to a predetermined position, means for receiving the articles delivered by the conveyor and delivering them to a predetermined position, means for rotating the articles while on said second means to wind any loose ends which may extend from the wound article, continuously rotating means for receiving articles successively from the second named means, means for feeding a wrapper to the continuously rotating means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, means for causing the first free end to be applied over the second named free end, oppositely disposed rotary mounted means for folding the wrapper partially across the opposed ends of the article, stationary means opposite the rotary mounted means and operating on the wrapper to effect a similar fold on each end of the article opposite to each fold made by the rotary mounted means, oppositely disposed rotary members for folding a half of the unfolded portion against the wrapper in a plurality of overlapping folds, means operating subsequently to said last named means for effecting a similar fold on the remaining unfolded portion of the wrapper to completely fold the wrapper about the ends of the article, and a second continuously operating conveyor for receiving the articles successively after the last named folding operation.

10. A wrapping machine comprising a continuously operating conveyor for delivering wound articles to be wrapped to a predetermined location, a continuously operating transfer wheel for receiving said wound articles successively as they are delivered by the conveyor, said transfer wheel including a plurality of spaced apart arms to receive the wound articles therebetween, means for causing rotation of said articles during at least a period of travel of the transfer wheel to rewind unwound parts of the rolls, and means for releasing the article at a predetermined position.

11. A wrapping machine comprising a continuously operating conveyor for delivering wound articles to be wrapped to a predetermined location, a continuously operating transfer wheel for receiving said wound articles successively as they are delivered by the conveyor, said transfer wheel including a plurality of spaced apart arms to receive articles therebetween, means for causing rotation of said articles dur-

ing at least a period of travel of the transfer wheel to rewind unwound parts thereof, means for releasing the article at a predetermined position, a continuously rotating wrapping wheel adapted to receive the articles when the articles are moved by the transfer wheel to said last named predetermined position, means for delivering wrappers consecutively to the wrapping wheel prior to the time the article is received by the transfer wheel, and means for wrapping the wrapper about the article while it is on the wrapping wheel.

12. A wrapping machine comprising a continuously operating conveyor for delivering wound articles to be wrapped to a predetermined location, a continuously operating transfer wheel for receiving said wound articles successively as they are delivered by the conveyor, said transfer wheel including a plurality of spaced apart arms to receive articles therebetween, means for causing rotation of said articles during at least a period of travel of the transfer wheel to rewind unwound parts thereof, means for releasing the article at a predetermined position, a continuously rotating wrapping wheel adapted to receive the articles when the articles are moved by the transfer wheel to said last named predetermined position, means for delivering wrappers consecutively to the wrapping wheel prior to the time the article is received by the transfer wheel, means for forming the wrapper about the article and gluing the free ends together, and a flexible member arranged adjacent the periphery of the wrapping wheel and adapted for engagement with the glued seam of at least one wrapped article during rotation of the wrapping wheel.

13. A wrapping machine comprising a continuously operating conveyor for delivering wound articles to be wrapped to a predetermined location, a continuously operating transfer wheel for receiving said wound articles successively as they are delivered by the conveyor, said transfer wheel including a plurality of spaced apart arms to receive articles therebetween, means for causing rotation of said articles during at least a period of travel of the transfer wheel to rewind unwound parts thereof, means for releasing the article at a predetermined position, a continuously rotating wrapping wheel adapted to receive the articles when the articles are moved by the transfer wheel to said last named predetermined position, means for delivering wrappers consecutively to the wrapping wheel prior to the time the article is received by the wrapping wheel, means for forming the wrapper about the article and gluing the free ends together, a flexible member arranged adjacent the periphery of the wrapping wheel and adapted for engagement with the glued seam of at least one wrapped article during rotation of the wrapping wheel, and means effecting end-folding operations on the wrapper during movement of the wrapping wheel.

14. A wrapping machine comprising a continuously operating conveyor for delivering wound articles to be wrapped to a predetermined location, a continuously operating transfer wheel for receiving said wound articles successively as they are delivered by the conveyor, said transfer wheel including a plurality of spaced apart arms to receive articles therebetween, means for causing rotation of said articles during at least a period of travel of the transfer wheel to rewind unwound parts thereof, means for releasing the article at a predetermined position, a continuously rotating wrapping wheel adapted to receive the articles

when the articles are moved by the transfer wheel to said last named predetermined position, means for delivering wrappers consecutively to the wrapping wheel prior to the time the article is received by the wrapping wheel, means for forming the wrapper about the article and gluing the free ends together, a flexible member arranged adjacent the periphery of the wrapping wheel and adapted for engagement with the glued seam of at least one wrapped article during rotation of the wrapping wheel, means effecting end-folding operations on the wrapper during movement of the wrapping wheel, and continuously operating means for engaging articles to remove them successively from the continuously rotating wrapping wheel.

15. A wrapping machine for wrapping articles of roll form comprising a continuously rotating wrapping wheel, means for delivering wrappers to the rotating wrapping wheel, means on said rotating wrapping wheel to clamp a wrapper, means to deliver a roll to be wrapped to the wheel and on top of the wrapper, means operating in timed relationship with the wrapping wheel to form the wrapper about the roll, means for gluing the free edges of the wrapper together, a pressure roller arranged adjacent the periphery of the wrapping wheel to press and roll against the wrapper at the glued edge, means for effecting partial opposite folds in the wrapper on each end of the roll, oppositely disposed continuously rotating means for folding a half of the remaining unfolded portion of the wrapper against the ends of the roll, and continuously rotating means for folding the remaining unfolded portion of the wrapper against the ends of the roll to complete the folding operation while the article is on the rotating wheel.

16. A wrapping machine for wrapping articles of roll form, and comprising a continuously rotating wrapping wheel, means for forming a wrapper about an article roll during the rotation of the wrapping wheel, means for effecting partial opposite folds in the wrapper on each end of the roll, oppositely disposed continuously rotating means for folding a half of the remaining unfolded portion of the wrapper against the ends of the roll, and continuously rotating means for folding the remaining unfolded portion of the wrapper against the ends of the roll to complete the folding operation.

17. A wrapping machine for wrapping articles of roll form, and comprising a continuously rotating wrapping wheel, means for forming a wrapper about an article roll during the rotation of the wrapping wheel, means for effecting partial opposite folds in the wrapper on each end of the roll, oppositely disposed continuously rotating means for folding a half of the remaining unfolded portion of the wrapper against the ends of the roll, continuously rotating means for folding the remaining unfolded portion of the wrapper against the ends of the roll to complete the folding operation, a continuously operating receiving conveyor to receive articles consecutively from the wrapping wheel, and guide means on the conveyor for positively removing the rolls from the wheel and preventing the rolls from remaining on the wrapping wheel.

18. A wrapping machine comprising a continuously rotating wrapping wheel, opposed continuously rotating folding members having bifurcated folding fingers, and a folding finger extending beyond the ends of the bifurcated fingers and adapted to engage the wrapper prior to the

engagement of the bifurcated fingers with the wrapper whereby a fold is caused by the projecting finger and overlapping folds are provided by the bifurcated fingers, said folding means effecting said folding operations while the article is on the continuously rotating wrapping wheel.

19. A wrapping machine comprising a continuously rotating wrapping wheel, opposed continuously rotating folding members having bifurcated folding fingers, a folding finger extending beyond the ends of the bifurcated fingers and adapted to engage the wrapper prior to the engagement of the bifurcated fingers with the wrapper whereby a fold is caused by the projecting finger and overlapping folds are provided by the bifurcated fingers, said folding means effecting said folding operations while the article is on the continuously rotating wrapping wheel, means releasing the roll from the wrapping wheel when the roll arrives at a predetermined position, and continuously operating means engageable with the roll for positively removing a wrapped roll from the transfer wheel when a roll arrives at said last named predetermined position.

20. The method of wrapping cylindrical rolls of wound material such as toilet paper and the like, which consists in feeding rolls of wound material to a predetermined position, rotating the rolls about their axes while moving said rolls in an orbit to effect rewinding of unwound parts of the rolls, then moving the rewound rolls in an orbit reversely to the first orbital movement, then applying a sheet of wrapping paper in tubular form about the cylindrical roll, gluing the free ends of the wrapper about the roll to provide a longitudinal seam thereon, and finally folding the ends of the wrapper against the ends of the roll while the roll is moving in the last named orbital path.

21. A machine for wrapping cylindrical rolls of wound material such as toilet paper and the like, comprising means for feeding rolls of wound material to a predetermined position, means for rotating the rolls about their axes while moving said rolls in an orbit to effect rewinding of unwound parts of the rolls, means for then moving the rewound rolls in an orbit reversely to the first orbital movement, means for then applying a sheet of wrapping paper in tubular form about the cylindrical roll, means for gluing the free ends of the wrapper about the roll to provide a longitudinal seam thereon, and means for finally folding the ends of the wrapper against the ends of the roll while the roll is moving in the last named orbital path.

22. A machine for wrapping rolls of wound material comprising means for delivering said wound rolls to a predetermined position, rotary transfer means for receiving the wound rolls at said predetermined position and moving them to a second predetermined position, means for rotating the rolls while on said transfer means to rewind any unwound parts thereof, and means for directly receiving said rewound rolls from said transfer means at said second position and applying a wrapper about the rolls.

23. A machine for wrapping rolls of wound material comprising means for delivering said wound rolls to a predetermined position, continuously rotating transfer means for receiving the wound rolls at said predetermined position and moving them to a second predetermined position, means for rotating the rolls while on said transfer means to rewind any unwound parts thereof, and means for directly receiving said rewound rolls from

said transfer means at said second position and applying a wrapper about the rolls.

24. A machine for wrapping rolls of wound material comprising an endless conveyor for continuously delivering said wound rolls to a predetermined position, continuously rotating transfer means for receiving the wound rolls at said predetermined position and moving them to a second predetermined position, means for rotating the rolls while on said transfer means to rewind any unwound parts thereof, and means for directly receiving said rewound rolls from said transfer means at said second position and applying a wrapper about the rolls.

25. A wrapping machine comprising means for delivering articles to be wrapped to a predetermined position, means for receiving articles successively from the delivery means and moving them through a predetermined path, means for feeding a wrapper to the article receiving and moving means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, and means for causing the first free end to be applied over the second named free end.

26. A wrapping machine comprising means for delivering articles to be wrapped to a predetermined position, means for receiving articles successively from the delivery means and moving them through a predetermined path, means for feeding a wrapper to the article receiving and moving means, means for holding the wrapper in a predetermined position, means for bringing the wrapper and article adjacent to each other, clamping means for clamping the wrapper about the outside of the article with the free ends of the wrapper projecting a predetermined distance beyond the clamping means, means for effecting a bend in the wrapper at one free end, means for applying an adhesive substance along the inner side of said free end, means engageable with the other said free end for holding said last named free end in a predetermined position, means for causing the first free end to be applied over the second named free end, and means for thereafter folding the wrapper tightly against the ends of each roll while on said article receiving and moving means.

27. A wrapping machine of the character described comprising cyclic conveying means having a plurality of seats for successively receiving articles to be wrapped, folding members pivotally mounted on said conveying means and extending between successive seats, a wrapper clamping member attached to said conveying means between each successive seat, cooperating wrapper clamping means carried by each of said folding members, means for moving said folding members to effect clamping of the leading end of a wrapper between said clamping member and said clamping means prior to reception of an article in a seat, means on said folding members for engaging and partially folding a wrapper about an article in a preceding seat, and means for moving said folding members to release said clamping of the leading end of a following

wrapper and to effect said partial folding operation of a preceding wrapper.

28. A wrapping machine of the character described comprising a rotary wrapping wheel having a plurality of seats for successively receiving articles to be wrapped, folding members pivotally mounted on said wheel and extending between successive seats, a wrapper clamping member attached to said wheel between each successive seat, cooperating wrapper clamping means carried by each of said folding members, means for moving said folding members to effect clamping of the leading end of a wrapper between said clamping member and said clamping means prior to reception of an article in a seat, means on said folding members for engaging and partially folding a wrapper about an article in a preceding seat, means for moving said folding members to release said clamping of the leading end of a following wrapper and to effect said partial folding operation of a preceding wrapper, means on said clamping member forming a pocket for retaining the leading end of a wrapper upon release of said clamping means, a second folding member movable to engage and partially fold a leading portion of a wrapper about an article after release of said clamping means, said pocket and said second folding member cooperating to bend the inner surface of a wrapper outwardly at the leading end thereof, and means for applying adhesive to said inner surface while bent outwardly.

29. Mechanism for transferring rolls of wound material from one predetermined position to another predetermined position, said mechanism including means for rewinding unwound portions of each of said wound rolls.

30. Mechanism for transferring rolls of wound

material from one predetermined position to another predetermined position, said mechanism including means for turning each of said rolls while moving between said positions to rewind unwound portions of said rolls.

31. Mechanism for transferring rolls of wound material from one predetermined position to another predetermined position, said mechanism including means for causing rotation of each of 10 said rolls during at least a portion of its traveling movement between said positions to rewind unwound portions of said rolls.

32. A machine comprising a transfer mechanism for receiving rolls of wound material at one predetermined position and moving them to a second predetermined position, and mechanism for rotating said rolls while on said transfer mechanism to rewind any unwound portions of 15 said rolls.

33. A machine for transferring rolls of wound material in succession, from one predetermined position to another predetermined position, comprising means for turning said rolls, while traveling between said positions, to rewind unwound portions of the rolls and thus present the same 20 successively in condition for wrapping at said second mentioned position.

34. A machine for transferring rolls of wound material in succession, from one predetermined position to another predetermined position, comprising means for turning said rolls, while traveling between said positions, to rewind unwound portions of the rolls and thus present the same 25 successively in condition for wrapping at said second mentioned position, and wrapping means for receiving the rolls at said second mentioned position.

CLARENCE J. MALHIOT.
